UNITED STATES PATENT OFFICE.

RICHARD BRADSHAW, OF MONTREAL, QUEBEC, CANADA.

METAL FURNITURE AND METHOD OF MAKING SAME.

Application filed October 18, 1922. Serial No. 595,350.

This invention relates generally to metal furniture and to the method or process of making same, and more particularly to metal beds and the manufacture thereof.

5 Metal beds produced in late years have been largely of the open frame or skeleton type and comparatively plain in design; that is to say, the head and foot frames have comprised posts, top and bottom rails extending 10 between the posts and fillers disposed between the rails. Such a type of bed is seriously limited as to the variety of designs that can be adopted. The variation of design has been produced by using tubes of various cross 15 sectional shapes, for example, tubes square, oblong or elliptical in cross section, and also by variations in the number and arrangement of the rails and fillers. In short, the design of present day metal beds is practically limited, for various manufacturing and 20 economic reasons, to the designs at present in vogue. This limitation has heretofore prohibited the production of metal beds in the solid or panelled designs or in designs 25 well known in wooden furniture construction, such, for example, as the Jacobean designs.

The present invention aims to provide for the manufacture of metal furniture in any of the designs in which wooden furniture can 30 be produced and at a cost materially below that of wooden furniture, at the same time maintaining the advantages of modern metal furniture, namely, strength, durability, lightness, imperviousness to atmospheric changes 35 and absence from crevices in which vermin may lodge. Any departure from the present designs of metal furniture, particularly beds, necessitates the use of panels or ornaments 40 of various types or both. Small panels may be inserted between the fillers and rails of existing designs but large panels are apparently prohibitive on account of the tendency of thin sheet metal to rattle. Furthermore, the application of such panels adds material- 45 ly to the cost of the article. Furthermore, ornamental posts, rails and fillers which vary in size from end to end or in cross sectional shape are, practically speaking, not available on account of the cost of making them and 50 the difficulty of assembling the parts after made. According to this invention panels of all descriptions, either plain or ornamented to reproduce carving, and also ornamental posts, rails and fillers may be produced very cheap-

ly and assembled with comparative ease so 55 as to produce metal replicas of standard wood furniture designs. The manner of construction is such that any tendency to rattle is entirely eliminated and at the same time strength, durability and simplicity of manu- 60 facture are not sacrificed.

The invention resides, broadly speaking, in employing sheets of stamped or embossed metal which are assembled, usually in pairs, into a frame to constitute panels. These 65 panels may occupy the spaces between existing fillers or may completely fill the frame. In the case of large panels which would tend, on account of the flexibility of the sheet metal, to rattle and thus betray the nature of the 70 material, the embossing may be of a nature to provide stiles, rails or the like integral with the panels and which will so stiffen the sheets of metal that rattling will be entirely 75 avoided. In assembling such sheets in pairs 80 to form panels, suitable stiffening members may be disposed between the sheets forming each panel, the said stiffening members being either separate from or connected directly 85 to the supporting frame. It will also be understood that the sheets may be embossed in such a manner as to completely enclose and 90 conceal the actual frame. On the other hand, where the material used is sufficiently stiff or is sufficiently stiffened by the embossing, 95 internal supporting members may be omitted even to the exclusion of an interior supporting frame. The panels, as previously stated, are each formed of two sheets where both 100 sides of a panel are visible, as for instance, in the case of bed ends. This is for the double purpose of concealing the convexity of the embossing on what may be termed the back of a sheet and for the purpose of concealing stiffening members if the same are 105 used. The sheets forming a panel may be both embossed or one may be plain. The manner of connecting the sheets may vary materially. The sheets may be connected together in any suitable way previous to assembly to a frame or the sheets may be separate and held together by a frame, or the sheets may be initially separate and individually connected to a frame during or after assembly. The sheets may be embossed in any suitable manner to represent plain panels with stiles and rails between, or raised panels with or without stiles and fillers, or

carved with or without stiles and fillers. In addition to the embossing the panels may be perforated to represent woven cane or any suitable form of grille work. In addition, 5 perforated panels may have integral unperforated portions embossed or not to represent carved or other medallions applied to woven cane for example. The sheets may be surface coated in whole or in part either 10 before or after embossing to duplicate the grain and colour of various kinds of wood.

In the accompanying drawings which illustrate a few of the possible embodiments of the invention;—

15 Fig. 1 is an elevation of a bed end provided with an inset panel.

Fig. 2 is a half section on an enlarged scale taken on the line 2—2, Figure 1.

20 Fig. 3 is a view similar to Figure 1 showing a bed end in which the frame is completely filled by panels.

Fig. 4 is a sectional view similar to Figure 2 on the line 4—4, Figure 3.

25 Fig. 5 is an end elevation of a bed end showing the panels entirely concealing a supporting frame.

Fig. 6 is a fragmentary sectional view on the line 6—6, Figure 5.

30 Fig. 7 is a sectional view showing one method of joining the sheets.

Figs. 8 and 9 are plan views illustrating different forms of embossed sheets.

Fig. 10 is a fragmentary view illustrating a 35 detail of construction.

35 Referring more particularly to the drawings, 21 designates the posts, 22 the top rail and 23 the bottom rail constituting a frame, for example, for a bed end. Fillers 24 are secured between the top and bottom rails.

40 A panel, designated as a whole by the numeral 25, is carried by the frame between adjacent fillers 24 and may be formed in a great variety of ways.

The panel shown in Figure 1 comprises 45 front and back sheets 26 and 27 respectively, either or both of which may be embossed to provide raised portions 28, as shown for example on the front sheet 26. The embossing may take any desired form and is not limited to the small raised panel illustrated. The embossing stiffens the sheet as will be readily understood, so that the same is substantially rigid under ordinary pressure and is entirely free from the rattling which is inherent to

50 large sheets of comparatively thin metal. The back sheet 27 may be embossed or may be plain as illustrated. If desired one or more spacers 29 may be provided between the sheets and connected to one or both of them by any 55 suitable means, such as electric spot welding.

This stiffener, where its use is necessary, serves to hold the central part of a comparatively large panel against buckling. The stiffener may end short of the frame members 60 as indicated in Figure 1, or may extend to

the frame members as indicated in Figure 3. The sheets forming the panel may be connected together in any suitable way, for example their edges may be let into any or all of the fillers or top and bottom rails so that 70 the sheets are held together by these members in addition to being supported in position. The sheets may also be connected together at their edges or at any other suitable points, for example by riveting, seaming or welding, so 75 as to form a panel which may be handled as a unit for insertion in a frame. It will also be understood that the sheets may be individually connected to the frame members or fillers or all of them by welding or by moulding 80 or by any other suitable means.

In Figures 3 and 4 there is illustrated a panel 25^a of sufficient size to fill the entire frame. In the embossing of the sheets forming this panel offset portions 30 may be provided, which on the backs of the sheets will 85 form recesses for the reception of fillers 24 or stiffeners 29, the difference being only that the term "filler" is applied to parts connected directly to the frame, while the term "stiffener" is applied to parts not connected directly to the frame. The embossing may include the provision of moulding 31 at the edges of the sheets, which moulding will 90 greatly stiffen the sheets at the periphery, 95 while the central portion will be stiffened by the offsets 30. The sheets thus formed may be assembled into a panel either separately from the frame or by the act of assemblage in the frame by any of the methods described 100 in connection with Figure 1. Alternatively, the edges of the sheets, which are in abutting relation when the sheets are assembled to form a panel, may be welded together so as to produce a unitary panel which may be inserted in the frame either with or without contained stiffeners. If the frame contains 105 fillers the sheets of the panel may be brought together on opposite sides of the fillers so as to completely encase the same. In such a construction the panel, in addition to being secured to the frame, may be secured to the fillers, for example by welding.

In Figure 5 there is illustrated a more elaborate form in which the frame is entirely encased in and concealed by the embossed sheets. In this construction the frame, which is the load carrying element, may be of rough and inexpensive construction. The embossed sheets, designated 25^b, are then 110 brought together on opposite sides of the frame and secured together by welding or otherwise. In Figure 7 there is illustrated a possible modification of the method of assembling sheets to form panels designed either 115 for insertion in frames or to encase frames in whole or in part. This modification resides in the provision of peripheral flanges 32 on the sheets designed for telescopic engagement. Preferably the flanges are 120

125 130

formed to fit very tightly together so that the panel formed will be free from rattling and also so that the exposed edge will be as nearly invisible as possible. Sheets thus formed may be connected together by spot welding the flanges or in any other suitable way. If the edge is exposed as in the case of sheets which encase a framework, the edge may be ground off in the finishing so as to be entirely invisible. In such an instance it is advisable that the welding, brazing or other means of connection be effected at the extreme edge and throughout the whole length thereof, so that after grinding or otherwise finishing there will be no visible seam and no crevice of any description.

In Figure 8 there is illustrated a perforated sheet 25^a. The perforations may be made to represent woven cane as illustrated and the sheet may if desired be additionally embossed in order to increase the similitude of the material represented. Such a sheet may include an unperforated portion 33 which may be embossed to stand out in relief from the sheet so as to represent a plaque or medallion attached to the caning or grille work. This portion 33 may have a smooth surface for decoration or may be in itself embossed to provide an ornamental design. In Figure 9 there is illustrated a panel sheet 25^a, part perforated and part unperforated, and having the offset portions 30 separating the perforated and unperforated portions and giving the appearance of stiles separating different types of panels. While each panel preferably comprises front and back sheets, it will be understood that the back sheet is not always an absolute necessity in the case of perforated panels, or that the back sheet may be applied only to the unperforated portion of sheets, that is to say, to the back of the medallion 33 and to the back of the solid centre panel of Figure 9. Obviously, however, two perforated sheets may be assembled together, proper care being necessarily exercised to secure proper registration of the openings therein.

The constructions illustrated in Figures 1 to 9 contemplate the use of comparatively thin sheets which, even with the embossing, would not have sufficient strength to render them available as load carrying elements, for example in a bed end. It will be understood, however, that in the case of a construction such as illustrated in Figure 5, it will be possible to eliminate the interior frame if the material of the embossed sheets is sufficiently heavy. It will also be understood that in many cases a solid frame throughout the structure is unnecessary. For example, in bed construction the only part of the framework actually under load is that extending from the side rail supports downwardly and that the remainder of the frame

is purely ornamental. It will therefore be evident that stamped sheets may be assembled together as in Figure 10 with comparatively short load carrying members 34 concealed therein only where absolutely necessary for strength, as for instance in the legs of furniture. As the sheets are designed to be assembled around such elements it is possible to provide a load carrying element 34 of any suitable shape to interlock with concave portions of the sheet and to extend to the surface where necessary to connect with elements externally attached, as for instance a side rail support 35 of a bed.

From the foregoing description it will be seen that the panels herein contemplated are designed for insertion in an exposed frame to fill the whole or a part of the frame or for the enclosure of the frame.

The use of such stamped sheets enables an infinite variety of designs to be obtained in the manufacture of metal furniture. Only a certain scope is possible in the variation of design employed in existing methods owing to the cost of producing the more elaborate designs and to the limitations imposed by the nature of the elements themselves, i. e., the tubular members employed. While more elaborate frame designs than that shown in Figure 1 for example may be produced, such elaboration entails the manufacture of a large number of separate ornamental parts which are themselves expensive. The cost of assembling these parts is very considerable, with the result that a definite limit is soon reached beyond which it is not practicable to go. According to the present invention ornamentation may be produced in any degree or style desired without in any way increasing the number of parts in the structure or materially increasing the cost. In fact, in a great many instances the number of parts in a structure is greatly decreased according to the present invention as compared with the production of a similar structure by existing methods. Moreover, the use of stamped sheets in the manner described enables many designs to be produced in metal furniture, which designs were heretofore impossible of production in metal.

It will be understood that the invention is not in any way limited to the details of construction herein disclosed and may include many modifications of form and of methods, for example, the use of fillings between the sheets of a panel to deaden the sound and eliminate any metallic ring if the panel is struck. Also in certain designs, the load carrying members 34 may be inserted after assembly of the sheets. The use of such load carrying members is obviously not limited to the legs of articles of furniture but may be employed in the construction of panels to be inserted in frames, more especially where the

panels have contact with the frames only at remote points. Sheets forming panels may also be applied in such a manner as to overlie the sides of a frame but to leave the outer edges of the posts and the top and bottom edges of the top and bottom rails respectively exposed.

The sheets composing each panel have hereinbefore been described and illustrated as each of the full size of the panel, but it will be understood that this is not essential and that the invention contemplates the assembly of front and back sheets of different sizes, for example, a plain back sheet of a size to fill the space between frame members and a smaller embossed front sheet attached in any suitable way to the back sheet, or conversely a front sheet embossed in part and a smaller plain back sheet covering only the embossed portion and either set flush in the back of the front sheet or projecting therebeyond to give a plain raised panel effect. Obviously a sheet may be embossed to represent fillers or other frame members and be otherwise plain and have attached thereto between the embossed portions separate embossed sheets.

Having thus described my invention, what I claim is;—

1. In metal bed end construction, a frame to stand on a floor and a pair of metal sheets 30 embossed to provide on their backs channels for reception of the frame members, the said sheets being disposed on opposite sides of the frame and connected together to completely enclose the frame. 35

2. In metal bed end construction, a sheet embossed to represent bed frame posts, rails and fillers, a second sheet, said sheets being flanged and telescopically assembled to one another, and a framework adapted to stand 40 on a floor contained between the sheets and supporting the same.

3. In metal bed end construction, a pair of metal sheets connected together at their edges to form a hollow body, and a framework 45 adapted to extend to and rest upon a floor disposed within said hollow body and supporting the same.

In witness whereof, I have hereunto set my hand.

RICHARD BRADSHAW.
